UNITED STATES PATENT OFFICE.

EDWARD E. CLEMENT, OF WASHINGTON, DISTRICT OF COLUMBIA, ASSIGNOR, BY
MESNE ASSIGNMENTS, TO FREDERICK C. STEVENS, OF ATTICA, NEW YORK.

TELEPHONE-EXCHANGE SYSTEM.

1,107,133.

Specification of Letters Patent. Patented Aug. 11, 1914.

Application filed March 27, 1905. Serial No. 252,305.

To all whom it may concern:

Be it known that I, EDWARD E. CLEMENT, a citizen of the United States, residing at Washington, in the District of Columbia, 5 have invented certain new and useful Improvements in Telephone-Exchange Systems, of which the following is a specification, reference being had therein to the accompanying drawing.

10 My invention relates to telephone exchange systems, and particularly to semi-automatic systems. In such systems a calling subscriber is answered by an operator who connects him with a trunk-line leading to 15 an automatic switching device whereby he may be connected with a wanted subscriber.

My present invention has for its object the production of such a system which shall employ a common battery at the central office 20 for all purposes, shall give the operators double supervision, shall provide for immediate recalls by a calling subscriber, shall give automatic ringing after completing each 25 connection, leaving repeated ringings to the operator until the subscriber answers, and shall generally embody all the desirable features and possibilities of a modern manual common battery system, including adaptability for registering measured service and 30 party-line work.

In the present system I employ a bridged battery grounded on one side, as usual, so that no possible objection can be raised on the score of possible electrolysis where a 35 balanced ground is employed. I employ supervisory relays and control relays, and make use of them for more than one purpose.

Many incidental objects and features are attained by and inhere in the invention, 40 which will sufficiently appear from the following detailed description and claims.

In the present system I use the switches shown and described in the patents to Keith and Erickson granted March 13, 1906, and 45 numbered 815,176 and 815,321, the latter applying to Figure 3 of this application, wherein the selector switch is used, and the former applying to Fig. 4 wherein the connector switch is used.

50 My invention is shown in the accompanying drawings, wherein—

Fig. 1 shows a subscriber's station with a transmitting device. Fig. 2 is a similar diagram showing the central office end of a subscriber's line-circuit, the cord-circuit and

trunk-jacks leading to the automatic switches. Fig. 3 shows a first selector switch. Fig. 4 shows a connector switch and the central office end of a subscriber's line-circuit.

60

Referring now to Fig. 1, I have shown a subscriber's station with apparatus usual in common battery systems, consisting of the transmitter T, receiver R, hook H, ringer Q and condenser C. In addition to this I have 65 shown the transmitting device, which consists of the following: the number-wheel d^3 , which transmits impulses corresponding to the ten thousand numeral of the line wanted, the number-wheel d^4 , which transmits impulses corresponding to the thousand numeral of the line wanted, the number-wheel d^5 , which transmits impulses corresponding to the hundred numeral of the line wanted, 70 the number-wheel d^6 , which transmits impulses corresponding to the ten numeral of the line wanted, the number-wheel d^7 , which transmits impulses corresponding to the unit numeral of the line wanted. When all five number-wheels are set the release magnet d 75 is connected to number 1 side of the line by the wire 110 through the contacts d^{18} , d^{19} ; and number 2 side of the line is grounded through the contacts d^{29} , d^{30} , wire 113, contacts d^{370} , d^{380} , wire 114, contacts d^{20} and d^{21} . 80 This ground energizes the line-relay at central which in turn operates the line-signal. The number-wheel d^3 is released by the magnet d and while operating breaks the line-circuits 1 and 2 through wires 110 and 111 85 and contacts d^8 and d^9 . This number-wheel after it has run down releases the number-wheel d^4 , which while operating makes and breaks the ground on line number 1, through 90 the wires 110, 123, and contacts d^{11} and d^{10} . 95 The number-wheel d^4 in running down cuts on the magnet d' , which controls the number-wheel d^5 . This number-wheel while operating makes and breaks the lines 1 and 2 through the wires 110, 111, 124, contacts d^{12} 100 and d^{13} . After the number-wheel d^5 has run down it cuts on the magnet d^2 , which in turn controls the number-wheel d^6 . This wheel while operating makes and breaks the lines 1 and 2 through the wires 110, 111, 125, 126 and contacts d^{14} and d^{15} . The number-wheel d^6 after it has run down releases the number-wheel d^7 , which while operating, grounds the line number 2 to wire 111, and contacts d^{17} and d^{16} . These number-wheels 110

while being set 'engage the pawls d^{32} , d^{33} , d^{34} , d^{35} and d^{36} , respectively, but do not make and break the contacts which they control, the pawls yielding while the wheels are being set. But while the wheels are running down to transmit the impulses, they make and break the contacts which they control. The last number-wheel d^7 , when run down, closes the contacts d^{30} and d^{31} which close the talking-circuit of the telephone. This talking-circuit is open while the various impulses are being transmitted to prevent the subscriber from receiving annoying clicks. This latter feature is shown and described in my allowed application Serial No. 225,058, filed Sept. 19, 1904, telephone system and apparatus, and as respects this feature this application is a division of the application mentioned.

20 Referring to Fig. 2, number 1 side of line from the subscriber's station terminates in a ground through the contacts n , n' of the cut-off relay N . Line number 2 from the subscriber's station terminates in the line-relay M , connected to battery through the contacts n^3 , n^4 of the cut-off relay N . The inner contacts n^2 , n^5 of the cut-off relay N , terminates in the springs j and j' of the jack J . One winding of the cut-off relay N is connected to ground, the other terminal being connected to the spring j^4 of the jack J . The spring j^3 of the jack J is connected to battery, as is also the thimble j^2 . The wires leading to the springs j , j' and j^4 are led to multiple-contacts z^{12} , z^{13} , z^{14} , in the connector switches, by the wires 11, 14 and 13, respectively. The lamp m is controlled by the line-relay M .

25 The cord-circuit consists of the following: the answering-plug P , calling-plug P' , supervisory or repeating relays S and S' , controlling-relay S^2 , pilot-relay S^3 , busy-back-relay E and the indicating magnets s and s' , which control the registering device, answering supervisory lamp s^2 and calling supervisory lamp s^3 . The tip p of the answering plug P , connected to the strand 16, and the tip p' of the calling plug P' , connected to the strand 18, are separated by condenser C , the sleeve p' of the answering plug P , connected to the strand 17, and the sleeve p' of the calling plug P' connected to the strand 19, are separated by the condenser C' . To the third conductor p^2 of the answering plug P , one terminal of the relay S^2 is connected by the wire 22, the other terminal being grounded. One terminal of the relay S^3 is connected to the third conductor p^2 of the calling plug P' by the wire 42, the other terminal being connected to the main battery bus-bar and from there to battery. One terminal of the lamp s^2 is connected to front contact s^{17} of the relay S^2 , the armature s^{18} being connected to battery, the other terminal of the lamp is connected

30 to the back contact s^{11} of the relay S by the wire 25, the contact s^{12} being grounded. It will be seen that the lamp s^2 will burn when the relay S is deenergized and the relay S^2 energized. The magnet s is controlled by the relay S , making and breaking the contacts s^{13} and s^{14} , the magnet s being connected to the contact s^{13} , through the wire 27, contacts s^{27} , s^{28} of the relay S^3 and wire 28. The magnet s' is operated by the making and breaking of the contacts s^{19} , s^{20} of the relay S' , the magnet s' being connected to the contact s^{19} , through the wire 26, contacts s^{30} , s^{31} , of the relay S^3 and wire 32. The relays S and S' are called the repeating relays because they are actuated directly by the impulses from the subscriber's transmitter and in turn actuate other relays. One terminal of the relay S is connected to the strand 16 by the wire 20, the other terminal being connected by the wire 29 to the contact s^{24} and by the contact s^{25} of the relay S^3 to battery wire 35. The upper contact s^{23} is grounded, so that when the relay S^3 is energized and attracts its armature the winding of the relay S is connected to the ground side of battery. The relay S' is connected to the strand 17 by the wire 21 and by the wire 30 to the contact s^{33} by the contact s^{34} of the relay S^3 to ground. The upper contact s^{32} is connected to battery through the wire 35, so that when the relay S^3 is energized and attracts its armature, relay S' is connected to the free side of battery. The battery is reversed by the relay S^3 for controlling the magnets in the transmitting device, which will appear later on. The lamp s^3 is connected to ground by the wire 43 to the contact s^{37} of the relay S^3 by the wire 45, and it will be seen that this lamp will only light when the relay S^3 is energized. The generator or busy-back G' is connected to the back contacts e^5 and e^7 of the busy-back relay E . The contacts e^6 and e^4 are connected to the strands 16 and 17, respectively, by the wires 36 and 37. One terminal of the relay E is connected to the back contact s^{22} of the relay S' by the wire 38, the contact s^{21} being grounded. The other terminal of the relay E is connected to the contacts k^2 and k^3 of the ringing key K , and by the wire 41 to contacts s^{35} and s^{36} of the relay S^3 , these contacts being connected to the sleeve p' of the calling plug P' by the wire 46. It will be seen that in order to connect current from the generator or the busy-back G , the relay S' and the relay S^3 will have to be energized and free side of battery connected to the sleeve p' of the calling plug P' . This only occurs when the test relay in the connector switch finds the line called busy, but this operation will be explained later on. The strand 19 is connected to the spring k of the ringing button or the key K by the wire 47, the contact k'

connected to battery by the wires 48 and 35. In the strand 18 there is inserted a test key U. The continuity of the strand 18 is broken when the springs u and u' are connected together for the purpose of testing a trunk to see whether it is busy. After the test is made the continuity of the strand 18 is completed through the contacts u' and u''. This test can be in the form of any standard 5 operation which will give the operator the characteristic click in the ear when a trunk is found that is busy. The trunk-wires leading from the first selector switch terminate in the springs j, j', the ring j² and the jack 10 J' by the wires 49, 50 and 51, respectively.

Referring now to Fig. 3, I have shown the first selector switch Z, which consists of the following: the vertical relay S⁵ normally connected to trunk-wire 49 to the side switch 15 z¹⁶ by the wire 55 and to ground by the wires 61 and 59, the rotary relay S⁶ being connected to the trunk-wire 50 through the side switch z¹⁷ by the wire 56 and to ground through the wires 60 and 59. The vertical 20 magnet s⁵ is operated by relay S⁵ through the normally closed contacts s⁶⁰ and s⁶¹ of the private relay S⁷. One terminal of the winding of the relay S⁷ is connected to the contact s⁵⁸ of the rotary relay S⁶ 25 by the wire 68, the other terminal of the winding being connected to battery through the wires 64 and 57, the normally open contact s⁵⁹ of this relay is connected to the contact x⁴ of the back release relay X by the wire 63. One terminal of the relay X is 30 connected to the blade of the side switch z¹⁸, the other terminal being connected to the private wiper z³ by the wire 70. One terminal of the release magnet W is connected 35 to battery by the wire 57 and the other terminal being connected to the contact x⁴ of the relay X by the wire 69. One terminal of the rotary magnet s⁶ is connected to the second point on the side switch z¹⁵ by the wire 40 66, and the other terminal being connected to battery by the wire 57. The wire 51 leading from the ring j² of the jack J', Fig. 2, is connected to the spring z⁶ by z⁵ to ground. It is also connected to the wiper z⁴. The 45 springs z⁵ and z⁶ are controlled by the cam z⁷, mounted on the spindle z. The spindle in stepping up for making its vertical movement does not affect these springs, but as soon as the spindle z begins to rotate the 50 contacts z⁶ and z⁵ are broken and ground is removed from the wire 51 and the wiper z⁴. The wipers z¹, z², z³ and z⁴ engage the contacts leading to the wires 490, 500, 511 and 55 510, respectively, which in turn lead to the connector switch Z' in Fig. 4.

Referring now to Fig. 4, I have shown the connector switch Z', which consists of the following: vertical relay S⁸, rotary relay S⁹, supervisory relays S¹⁰ and S¹¹, test relay X', 60 busy-back relay E', pilot relay V, ringing

relay Y, release magnet W', supervisory control relay S¹², vertical magnet s⁸, rotary magnet s⁹, resistance coil F, spindle z⁸, carrying the wipers z⁹, z¹⁰ and z¹¹, and condensers C² and C³. The vertical relay S⁸ 70 is connected to the trunk-wire 490 by the wire 78 and by wire 80 to the contacts s⁵⁴, s⁵³ of the relay S¹⁰ to ground. The rotary relay S⁹ is connected to the trunk-wire 500 by the wires 79, 104 to the contacts e³ and e² 75 of the relay E', wires 105 and 81 to contact s⁵⁶ and armature s⁵³ of the relay S¹⁰ to ground. The supervisory relay S¹⁰ is connected to the trunk-wire 72 by the wire 102 and to battery by the wire 82. The supervisory relay S¹¹ is connected to the trunk-wire 73 by the wire 99 and to ground by the wire 106. The ringing relay Y controlled by the rotary relay S⁹ is connected to the contact s⁴⁶ by the wires 102^a, 85, by the wire 88 to the wiper z¹¹, the resistance coil F is also connected to this wiper Z¹¹ and to battery by the wire 89. This places the ringing relay Y and the resistance coil F in multiple. The trunk-wires 490 and 72 are separated by 80 the condenser C²; the trunk-wires 500 and 73 are separated by the condenser C³. The test relay X' is normally connected across the wipers z⁹ and z¹⁰ through the following path: wire 92, contacts y³ and y² of the ringing relay Y, wire 96, contacts v³ and v² of the pilot relay V, wire 74 to wiper z⁹, the other terminal by the wire 91, contacts v⁶ and v⁵ of the relay V, wire 75 to wiper z¹⁰. The release magnet W' is normally under 90 control of the test relay through the following path: ground, wire 97, contacts v⁸ and v⁹ of the relay V, and wire 98 to contact x of relay X', the contact x' is connected to battery by the wire 90. The relay X' becoming energized would in turn energize the release magnet W' which would restore the switch to its normal position. The springs controlled by the relay V are held in their normal position by the latch v. This latch being attracted when the relay V is energized the springs assume other positions and are restored to their normal position again by the arm z¹² that is attached to the spindle z⁸, 100 when it assumes its normal position. The ringing relay Y is under the control of the rotary relay S⁹ and is operated when the wiper z¹¹ is at rest on the line wanted, leading to the line cut-off relay and the armature of the relay S⁹ being attracted in closing the contacts s⁴⁵, s⁴⁶. The vertical magnet s⁸ is operated by the vertical relay S⁸ when it is actuated and makes and breaks the contacts s⁴³ and s⁴⁴. The magnet s⁸ is connected 110 to the contact s⁴⁴ by the wire 84, and by the wire 86 to the contacts v¹⁰, v¹¹ and v¹² of the relay V. The rotary magnet s⁹ is operated by the rotary relay S⁹ when it is actuated and makes and breaks the contacts s⁴⁵ and s⁴⁶, the magnet s⁹ being connected to 120 130

4

the front contact s^{16} by the wire 85, by the wire 87 to the contacts v^{11} , v^{12} of the relay V to ground, the contacts s^{13} , s^{15} of the relays S⁸ and S⁹ being connected to battery by the wire 82. The busy back relay E' is controlled by the test relay X', one terminal being connected to battery and the other terminal being connected by the wire 103 to the contact x^2 of the relay X', the contact x^3 being connected to ground. The relay X' upon becoming energized, upon finding a busy line attracts its armature, closes the contacts x^2 and x^3 which energizes the relay E', which thereupon attracts its armatures, closes the contacts e and e' , opens the contacts e^2 and e^3 . The contact e' is connected to the trunk-wire 500 and the contact e is connected to wire 103 leading to the winding of E'. The relay X' is only energized momentarily, so means are provided for locking the busy back relay E'. It will be recalled that the winding of the busy back relay E is connected to the sleeve p' of the calling-plug P' through the contacts s^{35} , s^{36} of the relay S³, Fig. 2. It will be seen that the relay E' becomes locked through the winding of the relay E, and is under control of the operator. It was stated before that the release magnet W' was normally under control of test relay X', but after the wanted line is found and secured the pilot relay V becomes energized, releases the latch and its springs assume different positions. The contact v^8 leading to the release magnet W' and the contact v^9 leading to the contact x of the test relay X' were broken, and the contact v^8 is now in connection with the contact v^7 leading to multiple contacts in the first selector switches, Fig. 3, by the wires 83 and 511. It is also connected to the contact s^{50} of the relay S¹¹ by the wire 83. This places the release magnet under control of the operator, as will be described later on. The latch relay V in releasing opens the contacts v^{10} , v^{11} and v^{12} , which disconnect the wires 87 and 86, leading to the magnets s^8 , s^9 from ground. It also disconnects the test relay X' from its normal position across the wipers z^9 , z^{10} by breaking the contacts y^2 and v^3 and v^5 , v^6 . It also connects the trunk-wires 72 and 74 by the following path: contacts y^6 and y^5 of the ringing relay Y, wire 76, v^1 and v^2 to 74. It also connects the trunk-wires 73 and 75 by the following path: contacts y^8 and y^9 of the ringing relay Y, wire 77, contacts v^4 , v^5 of the relay V to wire 75. The subscriber or the operator, in ringing energizes the ringing relay Y. This relay when energized, opens the contacts y^5 and y^6 , y^8 and y^9 breaking the wires 72, 74, 73 and 75, and closes the contacts y^4 , y^5 , y^7 , y^8 , placing generator current from the bus-bars 94, 95 to the wires 74 and 75 leading to the wipers z^8 and z^{10} , and from there to the called subscriber's station. The contacts in

the ringing relay Y are broken in this manner to prevent current from flowing back over the wires 72 and 73 to the calling subscriber's station. The relay S¹² is controlled by the operator, and in turn controls the release of both the first selector switch and connector switch, as will be described later. One terminal winding is connected by the wire 101 to the contacts s^{51} and s^{52} of the relay S¹¹ to ground by the wire 106, the other terminal winding connected to the wire 510 which terminates in multiple banks engageable with the wiper z^4 of the first selector switch, Fig. 3. The wiper z^4 is connected to the thimble j^2 of the jack J', Fig. 2, by the wire 51. The contact s^{47} of the relay S¹² is connected to battery by the wire 82, and the contact s^{48} is connected to the contact s^{49} of the relay S¹¹ by the wire 100. It will be noticed that the winding of the relay Y connected to the wiper z^1 by the wire 88 is deenergized when the relay S⁹ is deenergized. For this reason the resistance coil F is also connected to the wiper z^1 so as to provide means for holding up the cut-off relay N of the called line.

The operation of my system is as follows: The subscriber in making a call sets his number-wheels corresponding to the number of the line he wishes to call. Referring to Fig. 1, in setting the first number-wheel d^3 the magnet d is connected to line 1 by the wire 115, contact d^{18} , d^{19} and wire 110. In setting the last number-wheel d^7 he grounds the line 2 by the following path. Wire 120, contacts d^{29} and d^{30} , wire 113, contacts d^{370} and d^{380} , wire 114, contacts d^{20} and d^{21} to ground. In setting the last number-wheel d^7 , the contacts d^{30} and d^{31} are broken, and the talking set connected by the wires 120 and 121 is disconnected. The ground placed on line No. 2 energizes the line-relay M, Fig. 2, through the contacts n^3 , n^4 , of the cut-off relay N. The line-relay M thereupon attracts its armature, and lights the line lamp m. It will be noticed that the magnet d is connected to the number 1 side of line to ground, and that number 1 side of line at central is grounded directly through the contacts n , n' of the cut-off relay N, so it will be seen that the magnet d is not affected by the act of signaling the central office, and the number-wheels of the transmitting device remain set. The operator perceiving the signal, inserts the answering-plug P into the jack J and the following connections and disconnections take place: The contacts j^3 and j^4 are closed which energizes the cut-off relay N, which attracting its armatures breaks the contacts n and n' , n^3 and n^4 , disconnecting the line-relay M and the ground. The line-relay M being disconnected extinguishes the line lamp m. The contacts n , n^2 , and n^3 , n^5 are closed, connecting the line 1 to the spring j of the jack J by the wire 130

3. It also connects the line 2 to the spring j' by the wire 4. The insertion of the plug P places battery in reversed order on the line-wires 1 and 2, through the repeating relays S and S' . Free side of battery is now placed on line No. 1 through the following path: armature n and contact n^2 of the cut-off relay N , wire 3, spring j , tip p , strand 16, wire 20, relay S , wire 29, contacts s^{24} and s^{25} of the relay S^3 , wire 35 to battery, and grounded side of battery is placed on line No. 2 by the following path: contacts n^3 , n^5 of the cut-off relay N , wire 4, spring j' , sleeve p' , strand 17, wire 21, relay S' , wire 30, contacts s^{33} , s^{34} of the relay S^3 to ground. Free side of battery now being placed on No. 1 side of line, the magnet d becomes energized and attracts its armatures, breaks the contacts d^{370} , d^{380} which disconnects ground from No. 2 side of the line, lifts the latch d^{37} which releases the first number-wheel d^3 . This number-wheel in running down makes and breaks lines No. 1 and 2 by the contacts d^8 and d^9 controlled by the pawl d^{32} . The making and breaking of the lines 1 and 2 actuates the relay S' the number of times corresponding to the ten thousand numeral of the line wanted. The relay S' making and breaking its contacts operates the vertical magnet s' whose armature engages a pawl and moves a number-wheel or indicator to the number corresponding to the number of impulses sent in over No. 2 side of the line; the magnet s' is controlled by the relay S' through the following path: battery B , wire 65, contacts s^{15} and s^{16} of the relay S^2 , whose armatures were attracted when the plug P was first inserted in the jack J ; wires 24, 31, contacts s^{19} , s^{20} of the relay S' , wire 32, contacts s^{30} , s^{31} of the relay S^3 , wire 26, magnet s' to ground. The relay S remains energized, its winding being in series with the winding of the magnet d to ground. It will be noticed that when the plug P was first placed into the jack J , the relay S^2 was energized and the relay S' de-energized until the impulses began to come in over No. 2 side of the line. The magnet s' at once made one step, and to provide for this contingency it, as well as the magnet s , is provided with one false movement, that is, in making the first step instead of indicating a numeral they indicate zero. After the number-wheel d^3 has run down it opens the contacts d^{18} , d^{19} , disconnects the magnet d and opens the contacts d^{20} , d^{21} to prevent ground being again connected to the No. 2 side of the line. It also lifts the arm d^{38} , carrying a pawl, which releases the second number-wheel d^4 . This number-wheel in running down makes and breaks a ground across No. 1 side of the line, through the contacts d^{10} and d^{11} , wires 123, 110. While these impulses are going in over No. 1 side of the line, No. 2 side of the line remains clear and the relay S' remains de-energized. The impulses coming in over No. 1 side of the line corresponding to the thousand numeral of the line wanted, actuate the relay S which in turn operates the magnet s a corresponding number of times. The magnet s is controlled by the relay S by the following path: battery B , wire 65, contacts s^{19} , s^{15} of the relay S^2 , wires 24 and 31, contacts s^{14} , s^{13} of the relay S , wire 28, contacts s^{27} , s^{28} of the relay S^3 , wire 27, magnet s to ground. The magnet s in operating moves its armature which engages a pawl and moves the number-wheel or indicator to the number corresponding to the thousand numeral of the line wanted. There now appears before the operator on her indicator the numbers corresponding to the ten thousand and thousand numerals of the line wanted. In the meantime, number-wheel d^4 after it has run down closes the contacts d^{22} , d^{23} , cutting on the magnet d' through the wire 117, the contacts d^{24} and d^{25} being closed when the number wheel d^5 was first set. The magnet d' is now connected from ground to the line-wire No. 2, but remains de-energized as the relay S' , Fig. 2, is connected to the grounded side of battery, and so the last three number-wheels remain set. The operator by means of the numbers appearing in her indicator knows the ten thousand and thousand numeral of the line wanted. She thereupon places the calling-plug P' into a trunk-jack leading to that group, after first using her test key U to see that the trunk is not busy. This test is accomplished in the ordinary manner and gives the operator a click in the ear if the trunk is busy.

In placing the plug P' into the trunk-jack J' the relay S^3 , one terminal of which is connected to battery through the wire 35, is energized by the following path: wire 42, third conductor p^2 , j^2 , wire 51, contacts z^6 , z^5 to ground, these contacts being controlled by the cam z^7 on the spindle z in the first selector switch Z , Fig. 3. The relay S^3 being energized, the following connections and disconnections take place: The contacts s^{37} , s^{38} are connected, closing the circuit of the lamp s^3 , causing it to glow. The contacts s^{35} and s^{36} leading to the busy back relay E are closed, but the means for closing its circuit or energizing it are not yet provided. The contact s^{34} is disconnected from the contact s^{25} and connected to the contact s^{23} , thus connecting the relay S to the grounded side of battery. The contact s^{33} is disconnected from the contact s^{34} and connected to the contact s^{32} , thus connecting the relay S' to the free side of battery. The contact s^{27} is disconnected from the contact s^{28} and connected to the contact s^{26} , thus disconnecting the magnet s and connecting the contact s^{12} of the relay S to the strand 18. The contact s^{20} is disconnected from the con-

tact s^{31} and connected to the contact s^{20} , thus disconnecting the magnet s' and connecting the contacts s^{19} of the relay S' to the strand 19. Battery now being reversed through the 5 windings of the relays S, S' , magnet d' , Fig. 1 is energized in series with the relay S' by the following path: wire 116, contacts d^{24}, d^{25} , wire 117, contacts d^{23}, d^{22} , wire 112, line wire 2, contacts n^3, n^5 of the cut-off relay N , 10 wire 4, spring j' , sleeve p' , strand 17, wire 21, relay S' , wire 30, contact s^{33}, s^{32} , wire 35, battery B. The magnet d' becoming energized lifts the latch d^{39} containing the pawl and releases the number-wheel d^5 , which in 15 running down makes and breaks lines Nos. 1 and 2 by the contacts d^{12}, d^{13} , controlled by the pawl d^{34} . The relay S' , Fig. 2, remains energized through the winding of the magnet d' , Fig. 1, while the impulses are 20 coming in affecting the relay S . The number-wheel d^5 in running down transmits impulses corresponding to the hundred numeral of the line wanted, actuating the relay S . The making and breaking of the contacts 25 s^{13}, s^{14} now send in impulses to the vertical relay S^5 , Fig. 3, by the following path: battery B, wire 65, contacts s^{15}, s^{16} of the relay S^2 , wire 24, and 31, contacts s^{14}, s^{13} , wire 28, contacts s^{27}, s^{26} , of the relay S^3 , wire 33, 30 strand 18, tip p , spring j wire 49, first contact in the side switch z^{16} , wire 55, vertical relay S^6 , wire 61 and ground. The relay S^5 corresponds to the makes and breaks caused by the relay S , and in turn attracts its armature correspondingly, and operates vertical magnet s^5 by the following path: ground, contact s^{57}, s^{56} , wire 67, contact s^{60} and s^{61} of the relay S^7 , wire 58, magnet s^5 , wire 57 and battery. Vertical magnet s^5 in operating 35 causes the spindle z carrying the wipers z^1, z^2, z^3 , and z^4 to step up in a vertical direction to the row of contacts leading to a connector switch containing the lines corresponding to the hundred numeral of the line 40 wanted. While the number-wheel d^5 was running down and transmitting impulses to the relay S the relay S' was energized and attracted its armatures. Just as the number-wheel d^5 runs down there is a momentary break before the magnet d^2 is cut on to line-wire 2. This momentary break allows the armatures of the relay S' to fall back the contacts s^{19} and s^{20} closing, places battery through the rotary relay S^8 by the following path: battery B, wire 65, contacts s^{15}, s^{16} of the relay S^2 , wires 24, 31, contacts s^{20} and s^{19} of the relay S' , wire 32, contacts s^{30} , and s^{29} , wire 34, strand 19, sleeve p' , spring j' , wire 50, first contact of side 45 switch z^{17} , wire 56, relay S^6 , wires 60, 59 and ground. The relay S^6 becomes energized, attracts its armatures and energizes the relay S^7 by the following path: ground, contacts s^{57}, s^{58} , wire 68, relay S^7 , wire 64, 50 wire 57 and battery. The relay S^7 being

energized causes the side switch to take one step, which cuts on the relay S^7 and the relay X is series to the wiper z^3 . It also connects the rotary magnets s^6 to ground through the side switch z^{15} . The rotary magnet now being cut on causes the spindle z to rotate and to continue to rotate until the wiper z^3 finds a contact that is not busy, that is to say, not grounded. So long as it is in connection with a grounded contact 55 the relay S' remains energized, being connected to the wiper z^3 in series with the relay X . The relay X being low-wound does not become sufficiently energized to attract its armatures. The instant the wiper z^3 finds a contact that is not busy, that is to say one free from grounds, the relay S' becomes de-energized, moves the side switches one more step; the rotary magnet s^6 is then disconnected and the spindle z ceases to rotate and the wire 49 leading from the spring j of the trunk-jack J' , Fig. 2, is connected to the wiper z^2 by the wire 53, and the trunk-wire 50 leading to the spring j' of the trunk-jack J' , Fig. 2, is connected to the wiper z^2 by 60 the wire 54. The relay S^7 is disconnected from the wiper z^3 and the relay X connected from the wiper z^2 direct to ground. The vertical relay S^5 and rotary relay S^6 are now disconnected from the trunk-wires 65 49-50, respectively. The instant the spindle z began to rotate the cam z^7 opened the contacts z^5 and z^6 , which disconnected ground from the wire 51 leading to the ring j^2 of the trunk-jack J' , Fig. 2, and from there to the 70 third conductor p^2 , wire 42, relay S^8 , wire 35, battery B. This ground being removed, the relay S^8 becomes de-energized and battery is reversed through the windings of the relays S and S' so that battery is now flowing over the wires 1 and 2 as when the call was first answered. The reversing of this battery causes current from the free side to flow out on line No. 1 through the winding of the relay S and grounded side to flow out 75 on No. 2 side of the line through the winding of the relay S' . The magnet d^2 , Fig. 1, is now connected to the line 2 by the following path; the number-wheel d^5 having run down: contacts d^{27}, d^{28} , wire 118, contacts d^{26}, d^{25} , wire 117, contacts d^{23}, d^{22} , and wire 112. Grounded battery now being on No. 2 side of the line this magnet d^2 is not affected, and the last two number-wheels d^6 and d^7 remain set. When the spindle z ceased to rotate and the wipers rested on contacts leading to a trunk in the desired group, the relay S^2 , Fig. 2, was again energized by a ground through the following path: Fig. 4, wire 103, contacts s^{52}, s^{51} of the relay S^{11} , wire 101, relay S^{12} , wire 510, Fig. 3, wiper z^4 , wire 51 in Fig. 2, j^2, p^2 , wire 42, relay S^3 , wire 35 and battery. The relay S^3 thereupon being energized again reverses battery on 80 the line, that is, grounded battery is sent out 85 120 125 130

on No. 1 side of the line through the relay S and free side of battery is sent out on No. 2 side of the line through relay S'. Free side of battery now being on No. 2 side of the line the magnet d^2 lifts the latch d^{40} and releases the number-wheel d^6 . This number-wheel in running down makes and breaks the lines 1 and 2 by contacts d^{18} , d^{14} , controlled by the pawl d^{35} . These impulses corresponding to the ten numeral of the line wanted actuate the relay S, the relay S' being energized through the magnet d^2 , while these impulses are coming in. The making and breaking of the contacts in the relay S according to the ten numeral of the line wanted operate the vertical relay S⁸ in the connector switch z' , Fig. 4, by the following path: Fig. 2, battery B, wire 65, contacts s^{15} , s^{16} , relay S², wires 24 and 31, contacts s^{14} , s^{13} of relay S, wire 28, contacts s^{27} , s^{26} , of relay S⁸, wire 33, strand 18, p , j , wire 49, Fig. 3, wire 53, wiper z' , wire 490, Fig. 4, wire 78, relay S⁸, wire 80, contacts s^{54} , s^{53} of the relay S¹⁰ to ground. The relay S⁸ in turn operates the magnet s^8 correspondingly by the following path: battery B, wire 82, contacts s^{43} and s^{44} of the relay S⁸, wire 84, magnet s^8 , wire 86, contacts v^{10} , v^{11} , v^{12} of the relay V and ground. The operating of this magnet s^8 causes the spindle z^8 carrying the wipers z^9 , z^{10} , z^{11} to step up in a vertical direction to the row in which the desired line is located.

Referring now to Fig. 1, after the number-wheel d^6 has run down the contacts d^{27} , d^{28} are opened and the magnet d^2 disconnected, the latch d^{41} containing the pawl is lifted and the number-wheel d^7 released. No. 1 side of the line is clear and the relay S becomes deenergized. The impulses are sent in over the No. 2 side of the line by the number-wheel d^7 running down making and breaking the contacts d^{16} and d^{17} , controlled by the pawl d^{36} . These makes and breaks send in impulses from ground over No. 2 side of the line actuating the relay S' corresponding to the unit numeral of the line wanted. The relay S' by making and breaking its contacts operates the relay S⁹ in the selector switch Z', Fig. 4, by the following path: Fig. 2, battery B, wire 65, contacts s^{15} , s^{16} of the relay S², wires 24 and 31, contacts s^{20} and s^{20} of the relay S', wire 32, contacts s^{20} and s^{20} of the relay S⁸, wire 34, strand 19, p' , j' , wire 50; Fig. 3, continuation of wire 50, wire 54, wiper z^2 , wire 500 and in Fig. 4, wire 79, relay S⁹, wire 104, contacts e^3 and e^2 of the relay E, wires 105, 81, contacts s^{55} , s^{53} of relay S¹⁰ to ground. The relay S⁹ in turn operates the magnet s^9 correspondingly by the following path: battery B, wire 82, contacts s^{45} and s^{46} of the relay S⁹, wire 85, magnet s^9 , wire 87, contact v^{11} and v^{12} of the relay V. The armature of the magnet s^9 when operated causes the spindle carrying the wipers z^9 , z^{10} and z^{11} to

rotate and come into contact with the line desired. These wipers pass rapidly over the contacts z^{12} , z^{13} , and z^{14} , the latter of which are grounded through the cut-off relays N. The period of engagement of the wipers with these contacts is of such short duration that the ringing relay Y which is connected to the wipers z^{11} does not have time to pull up, this relay being sluggish in action, while the spindle carrying the wipers operates rapidly. When finally the wipers come to rest on the desired contacts, the relay S⁹ having permanently pulled up through the deenergization of the relay S', current now energizes the ringing relay Y through the cut-off relay N by the following path: battery B, wire 82, contacts s^{46} , s^{15} , wire 85, relay Y, wire 88, wiper z^{11} , contact z^{14} , wires 13 and 15, cut-off relay N and ground. The relay Y when energized attracts its armature and the following connections and disconnections are made: The contacts y and y' are closed, energizing the relay V by the following path: battery B, wire 90, contacts y and y' , wire 93, relay V to ground. The contacts y^2 , y^3 are broken, disconnecting the test relay X' which was normally connected across the wipers z^9 and z^{10} . The contact y^5 is disconnected from the contact y^6 which opens the wire 72 and is connected to the contact y^4 leading to generator by wire 94. The contact y^8 is disconnected from the contact y^9 breaking the wire 73 and connected to contact y^7 leading to the other side of generator by wire 95. Generator current is now connected across the wipers z^9 and z^{10} by the following path: wire 74, contacts v^1 and v^2 , wire 76, contacts y^4 and y^5 , wire 94 to one side of generator, and by the wire 75, contact v^5 and v^4 , wire 105 77, contacts y^8 , y^7 , wire 95 to the other side of generator. When the relay V was energized it tripped the latch v and the following connections and disconnections were made: Contact v^2 was disconnected from the contact v^3 and connected to the contact v' . The contact v^5 was disconnected from the contact v^6 and connected to the contact v^4 . Contact v^8 was disconnected from the contact v^9 and connected to contact v^7 . This takes the release magnet W' from under control of the test relay X' and places it under direct control of the operator by the following path: ground, release magnet W', wire 97, contacts v^8 and v^7 , wire 83, contacts s^{40} and s^{49} of the relay S¹¹, wire 100, contacts s^{47} , s^{48} of the relay S¹², wire 82 to battery B. It is controlled by the operator in the following manner: So long as the calling-plug P' is in the trunk jack J' the relay S¹² is energized and the contacts s^{47} and s^{48} are broken and the circuit of the release magnet W' is open. The relay S¹² is deenergized when the called subscriber has answered by the relay S¹¹ being energized and 125 130

attracting its armatures opening the contacts s^{51} and s^{52} which opens the circuit of the relay S^{12} , but at the same time the contacts s^{49} and s^{50} are broken and the circuit of the release magnet W' remains open. The contacts v^{10} , v^{11} and v^{12} of the relay V are also broken and the magnets s^8 and s^9 are disconnected.

Referring again to Fig. 1, the number-wheel d^7 after it has run down closes the contacts d^{30} and d^{31} , which closes the talking-circuit through the wires 120 and 121, and the calling-subscriber is connected to the called subscriber by the means of the cord-circuit Fig. 2; first selector Z , Fig. 3; connector Z' , Fig. 4. It will be noticed that ringing current is sent to the called subscriber automatically by the last number-wheel running down in the calling-subscriber's transmitting device.

Referring now to Fig. 2, it will be seen that the operator has double supervision over the connections by means of the lamps s^2 , s^8 . The lamp s^2 remains lighted so long as the relay S^3 is energized. It becomes de-energized when the called subscriber has answered in the following manner: The supervisory relays S^{10} , S^{11} are energized when the called subscriber takes down his telephone in answering, and their armatures are attracted. In the relay S^{11} the contacts s^{51} , s^{52} are broken. This opens the circuit of the relay S^3 , Fig. 2, which thereupon lets its armatures fall back extinguishing the lamp s^8 . Battery is also reversed through the relays S and S' , but does not affect anything, as all the number-wheels at the subscriber's station have run down. The contacts leading to the magnets s and s' are again connected in the relay S^3 , but remain open by the contacts s^{13} and s^{14} of the relay S being broken. The contacts s^{19} and s^{20} of the relay S' being broken the armatures of the relays S and S' being attracted during conversation. The ringing relay Y , Fig. 4, is disconnected by the contacts s^{45} and s^{46} of the relay S^8 being broken after ringing. The resistance coil F connected permanently to battery by the wire 89, is connected to the wiper z^{11} , and holds up the cut-off relay N when the ringing relay Y is disconnected. Suppose the called subscriber did not answer the ring of his telephone, which was at first done automatically by the last number-wheel in the calling subscriber's set, the operator having supervision over this called subscriber's line notices the lamp s^8 continuing to glow, she at once knows the subscriber has not answered his telephone, and by pressing the lever k of the ringing-key K against the contact k' , which is connected to battery by the wire 35, she energizes the relay S^9 in a connector switch Z' , Fig. 4, which attracts its armature, closes the contact s^{45} and s^{46} , which energizes the relay

Y as in the former case, and ringing current is again sent out over the called subscriber's line. This ringing can be repeated until the subscriber answers. When the called subscriber removes his telephone, he closes the circuit through the relays S^{10} and S^{11} which attract their armatures. The contacts s^{54} , s^{55} and s^{53} are broken and the vertical relay S^8 and the rotary relay S^9 are disconnected. The contacts s^{50} and s^{49} of the relay S^{11} are broken to prevent the release magnet W' getting current, the contacts s^{52} and s^{51} which control the circuit of relay S^{12} are also broken allowing its armature to fall back. The moment the contacts s^{51} and s^{52} are broken the relay S^3 in Fig. 2 becomes de-energized and the lamp s^3 extinguished, notifying the operator that the called subscriber had answered. At the end of the conversation both subscribers hang up their telephones, causing the lamps s^2 and s^3 to glow, thus notifying the operator that she may take down the connection. The operator always pulls the trunking or calling plug P' first, so as to provide for a recall by the calling subscriber in case there happens to be one, the reason for which will be described later. In taking down the answering-plug P the relay N becomes de-energized and the line-relay M is again connected to line ready for another call. In taking down the calling-plug P' , the circuit of relay S^{12} , Fig. 4, was broken, it thereupon becomes de-energized and its armature falling back closes the contacts s^{47} , s^{48} , which places battery on the contact s^{49} of the relay S^{11} . The relay S^{11} being de-energized on account of the calling-subscriber having hung up his telephone, the contact s^{50} is in connection with contact s^{49} and battery is furnished the release magnet W' , which becoming energized restores the connector switch Z' to its normal position. The spindle z^8 , carrying the arm z^{12} descends and places the contact-springs of the relay V under control of the latch v . The contacts s^{40} and s^{50} of the relay S^{11} also connect battery to the relay X , switch z , Fig. 3, by the following path: wire 511, wiper z^8 , wire 70, relay X , side-switch z^{18} , wire 71 to ground. This relay attracting its armature closes the contacts v^4 and v^5 , which closes the circuit of the release magnet W , and restores the switch z and all its parts to their normal position.

Referring now to a recall by the calling subscriber, that is if he wishes to call for another number at once, the following operation takes place: The calling subscriber at the end of a conversation desiring to be connected with another party, immediately sets his number-wheels as in the first case. The release magnet controlling the first number-wheel is connected to No. 1 side of the line to ground, the plug P' still being in the trunk jack J' and the relay S^9 being ener-

gized, its armature is attracted, and ground-
ed battery is sent out over No. 1 side of the
line through the relay S, and free side of the
battery sent out on No. 2 side of line through
the relay S'. The relay S, jointly controlling
the supervisory lamp s² is not affected and
the lamp continues to burn, and the magnet
controlling the first number-wheel of the
transmitting device is also not affected. At
this juncture both supervisory lamps are
10 glowing, and the operator taking down the
calling-plug P' first, deenergizes the relay
S² whose armatures thereupon fall back,
current is now reversed through the relays
S and S' and the relay S attracts its arma-
ture and at once extinguishes the lamp s².
The operator noticing that the answering
supervisory lamp s² is extinguished, upon
15 withdrawing the calling-plug at once knows
there is a recall and looks to her indicator
for the number as in the first case. These
numbers come in exactly the same manner
as first described and the operation is iden-
tical, so there is no need of further descrip-
tion.

20 Suppose the line called for was busy when
the wipers z⁹ and z¹⁰ came into contact with
the terminals z¹² and z¹³ leading to the wires
3 and 4 of the line circuit. In this case there
25 would be bridged battery on these wires fur-
nished by the relays S and S' in the opera-
tor's cord-circuit. The test relay X' is nor-
mally connected across the wipers z⁹ and z¹⁰
30 through the contacts y² and y³ of the relay
Y, wire 96, contacts v² and v³ of the relay V,
wire 74 to wiper z⁹, the other terminal be-
ing connected by wire 91, contacts v⁵ and v⁶
35 of the relay V, wire 75 to the wiper z¹⁰. The
test relay X' would then become energized,
attract its armature, close the circuit of the
40 release magnet W' by the following path:
battery B, wire 90, contacts x' and x, wire
98, contacts v⁹, v⁸, of the relay V, wire 97,
magnet W' to ground. The release magnet
45 W' being energized would restore the
switch to its normal position. The contacts
x², x³ being closed complete the circuit of
the busy back relay E' by the following
50 path: x², x³, wire 103, E', to battery. The
relay X' only attracts its armature momen-
tarily, so means are provided to lock the re-
lay E'. This is accomplished by the follow-
55 ing path: battery B, winding E', contacts
e, e', wire 500, and in Fig. 3, wire 500, wiper
z², wire 54, wire 50; and in Fig. 2, j', p', wire
46, contacts s³⁶, s³⁵ of the relay S', wire 41,
60 contacts k² and k³ of ringing key K, wind-
ing of the relay E, wire 38, contacts s²², s²¹
of the relay S' to ground. The relay E'
then remains locked through the relay E,
65 which in turn becomes energized and at-
tracting its armatures closes the contacts e⁴,
e⁵ and e⁶, e⁷, and connecting generator cur-
rent for a busy-back signal to the strands
70 16 and 17, respectively, and from there to

the calling subscriber's line, notifying him
that the line called for was busy. He there-
upon hangs up his telephone and deener-
gizes the relays S and S', and causes the
75 lamp s² to glow, which notifies the operator,
who thereupon takes down the connection.
Taking down the calling-plug P', she opens
the circuit of the relay S¹², Fig. 4, and lets
its armature fall back, closing the contacts
80 s⁴⁷ and s⁴⁸, which places battery on the re-
lay X in the first selector switch Z, Fig. 3,
by the following path: battery B, wire 82,
contacts s⁴⁷ and s⁴⁸, wire 100, contacts s⁴⁶
and s⁵⁰ of the relays S¹¹, wire 511, and in
85 Fig. 3, wiper z², wire 70, relay X, side
switch z¹⁸, wire 71 to ground. The relay X
thereupon becomes energized and attracting
its armature closes the contacts s⁴ and s⁵,
which closes the circuit of the release mag-
net W, this magnet becoming energized re-
85 stores the selector switch Z to its normal po-
sition.

While I have illustrated and described the
impulse transmitter at the substation with
five wheels and three magnets, it should of
course be understood that with slight altera-
90 tion one magnet will govern all the wheels in
practice, the showing herein being simplified
for diagrammatic purposes.

While I have stated that my present in-
vention is particularly applicable to semi-
automatic systems, there are certain features
thereof which may be employed in any sys-
tem. Such for example is the arrangement
95 of the latent signal sending device or im-
pulse transmitter at the subscriber's station.
There must be impulse actuated signaling
or connecting devices to respond to such a
transmitter, but obviously these may be of
any desired type without affecting or chang-
100 ing this point of invention. I shall there-
fore claim such a combination broadly, ir-
respective of the type of central office con-
necting devices.

Having thus described my invention what
110 I claim and desire to secure by Letters Pat-
ent is:

1. In a telephone exchange system, a sub-
scriber's line, a substation connected to said
line, a talking set at the substation, an im-
pulse transmitter also at the substation com-
prising a pair of make and break wheels
and contacts governed thereby, said wheels
adapted to be set so as to make and break
said contacts a determinate number of 115
times, a magnet and a retaining device con-
trolled thereby for holding the first wheel
when set, a retaining device for the second
wheel controlled by the movement of the
first wheel, a line signal connected to the 120
line normally and adapted to be operated
when the wheels are set without operating
the said magnet at the substation, a connec-
tive circuit adapted to be brought into con-
nection with said line, a receiving device 125
130

associated with said circuit and adapted to be affected by impulses from the substation, and means becoming operative in making connection with the line to change the 5 course of current through the line circuit so as to energize the retaining magnet at the substation, substantially as described.

2. In a telephone exchange system, a subscriber's line, a substation connected to said 10 line, a talking set at the substation, an impulse transmitter also at the substation comprising a pair of make and break wheels and contacts governed thereby, said wheels adapted to be set so as to make and break 15 said contacts a determinate number of times, a magnet and a retaining device controlled thereby for holding the first wheel when set, a retaining device for the second wheel controlled by the movement of the 20 first wheel, a line signal connected to the line normally and adapted to be operated when the wheels are set without operating the said magnet at the substation, a connective circuit adapted to be brought into connection with said line, a receiving device 25 associated with said circuit and adapted to be affected by impulses from the substation, and means becoming operative in making connection with the line to change the direction of current through the line circuit 30 so as to energize the retaining magnet at the substation, substantially as described.

3. In a telephone exchange system, a subscriber's line, a substation connected to said 35 line, a talking set at the substation, an impulse transmitter also at the substation comprising a pair of make and break wheels and contacts governed thereby, said wheels adapted to be set so as to make and break 40 said contacts a determinate number of times, a magnet and a retaining device controlled thereby for holding the first wheel when set, a retaining device for the second wheel controlled by the movement of the 45 first wheel, a line signal connected to the line normally and adapted to be operated when the wheels are set without operating the said magnet at the substation, a connective circuit adapted to be brought into connection with said line, a receiving device 50 associated with said circuit and adapted to be affected by impulses from the substation, and means becoming operative in making connection with the line to reverse the current through the line circuit so as to energize the retaining magnet at the substation, 55 substantially as described.

4. In a telephone exchange system, a subscriber's line, a substation and a central station connected to said line, an impulse transmitter at the substation adapted to be set to make and break or ground the circuit according to a predetermined code, a magnet controlling the impulse transmitter and 60 when the latter is set, connected from one

side of the line to ground, a connective terminal and a line signal associated with the line at the central station, a main battery thereat grounded on one side and normally connected across the line with its ground 70 on the same side as the substation controlling magnet, a central station circuit adapted to be brought into connection with the line, and means thereby becoming operative to reverse the battery on the line, so as to 75 direct current through the said controlling magnet and release the substation signal device, substantially as described.

5. In a telephone exchange system, a subscriber's line, a substation and a central station connected to said line, an impulse transmitter at the substation adapted to be set to make and break or ground the circuit according to a predetermined code, a magnet controlling the impulse transmitter and 80 when the latter is set, connected from one side of the line to ground, a spring jack and a line signal magnet associated with the line at the central station, a main battery grounded on one side and normally connected 85 across the line with its ground on the same side as the substation controlling magnet, a cut-off relay connected to the jack and adapted when energized to cut off the line signal magnet and reverse the battery connections, a plug and cord circuit adapted to coöperate with the line jack, a signal receiving device associated with the cord to respond to the substation transmitter, and means to energize the cut-off relay when 90 the plug is inserted in the jack, substantially as described.

6. In a semi-automatic telephone exchange system, a line circuit, a substation and a central station, an impulse transmitter at the substation comprising a plurality of elements adapted to be set to transmit successive numbers, a retaining magnet for said transmitter retaining each number as set, and grounded from one side or the other of the line as the numbers are set and go in, a spring jack for the line at the central office and a cut-off relay associated therewith, a cord circuit and an answering plug, an impulse receiver associated with 105 the cord and adapted to respond to one or more of the numbers transmitted, a trunk circuit and an automatic switching device connected therewith, multiple line terminals of subscribers' lines in said switch, 110 means to connect the cord to the trunk; a main battery grounded on one side and normally connected through the cut-off relay contacts to the line with its ground on the same side as the normal connection of the 115 substation controlling magnet, means operable when the plug is inserted in the line jack for energizing the cut-off relay to remove the normal battery connections, and 120 reversed battery connections simultaneously 125 130

established, whereby the substation magnet is energized and one or more numbers transmitted; together with means becoming operable on connecting the cord with the trunk 5 to again reverse the battery connections, thereby again to release the substation transmitter to send controlling impulses to the automatic switch to move the latter into connection with a wanted line terminal, substantially as described.

7. In a telephone exchange system, subscribers' lines and central office apparatus for interconnecting them, latent signal circuit changers at the substations each composed of a plurality of transmitting elements with magnetic controlling means permitting operation of the elements to send successive number groups, said magnets being successively connected from one 15 side of the line and the other to ground, said central office apparatus comprising automatic signal and switching devices operating successively to connect a line calling by a plurality of steps in accordance with the numbers transmitted, to the line wanted, and means operated in making the successive steps to change or reverse the battery connections from step to step so as to produce successive operations of the substation number elements in proper order, substantially as described.

8. In a telephone exchange system, a subscriber's station and latent signal impulse transmitting device with a talking set, said 35 signal transmitting device comprising means for setting up the transmission of a plurality of groups of impulses and thereafter transmitting the same successively, together with means operated by the setting means 40 to disconnect the talking set and to maintain such disconnection until the impulse transmitter has transmitted all the groups and finished its operation, substantially as described.

45 9. In a telephone exchange system, a subscriber's line and a substation impulse transmitter, a line jack and signal at a central office, trunk lines at the central office equipped with automatic connector switches 50 having subscribers' line terminals, an operator's cord circuit for interconnecting the said subscriber's line with any of said trunk lines, thereby placing the automatic switching means under control of the subscriber's transmitter, means for differentiating the calling from the called end of the connected circuit thus formed, and for supplying current thereto independently, supervisory 55 relays in the cord circuit adapted to be controlled respectively by the calling and called subscribers, and means for restoring the automatic switches to inactive positions at the end of a conversation, substantially as described.

60 65 10. In a telephone exchange system, a sub-

scriber's station with a telephone and an impulse transmitter, a line circuit therefrom terminating in a spring jack at a central office, an operator's cord circuit with a terminal plug coöperating with said jack, a trunk 70 indicating device associated with said cord circuit, means controllable in making connection with the line to place said indicating device under control of the subscriber's transmitter, a selector switch connected to a 75 trunk, and magnetic operating means therefor, means for connecting the subscriber's line through the cord and trunk with said switch, means operable upon making said connection to remove the cord indicator from the subscriber's control and transfer the same to the selector switch magnetic devices, 80 trunk connections from said selector switch to connector switches containing subscribers' terminals and also having magnetic control, 85 with means operable upon effecting connection through a selector switch to a desired connector to remove the selector magnets from the subscriber's control and transfer said control to the connector controlling 90 magnets; a ringing relay and means whereby at the end of the operation of the subscriber's transmitter the said ringing relay is automatically operated to connect generator to the wanted subscriber's line; means for 95 dividing the calling and the called end of the circuit and for supplying current to the calling and the called subscriber separately, together with supervisory signal magnets in the operator's cord circuit controlled respectively by the calling and the called subscriber, and means controlled by the operator to actuate the said ringing relay for repeated ringing if the wanted subscriber does not immediately answer, substantially as described.

110 11. In a telephone exchange system, line circuits, operator's cord circuits and trunk circuits with automatic switches connected thereto, means initiated by an operator in response to a call from the subscriber to effect a connection through the automatic switches to a wanted line, said switches being under the control of the calling subscriber in selecting and connecting with the wanted line, together with means under the control of the operator for releasing said switches at the termination of a conversation, substantially as described.

115 12. In a telephone exchange system, a subscriber's line terminating in a spring jack at a central office, a trunk line, means initially controlled by an operator in response to the subscriber's call for connecting his line with said trunk line, an automatic switch, controlled thereafter by the subscriber and operating to connect said trunk line with a wanted line, and means controlled by the operator for disconnecting the lines, substantially as described.

13. In a telephone exchange system, subscribers' lines and connective circuits therefor, supervisory signals associated with said connective circuits, controlling magnets therefor, and automatic switching devices controlled by said magnets, substantially as described.

14. In a telephone exchange system, subscribers' lines, an operator's cord-circuit, 10 trunk lines, visual means controlled by the subscribers for indicating to the operator a trunk leading to a desired line, an automatic

switch also controlled by the calling subscriber for effecting the connection of the trunk line with the desired line, and means 15 under the control of the operator for effecting a restoration of the switch to its normal condition at the end of the conversation.

In testimony whereof I have affixed my signature in presence of two witnesses.

EDWARD E. CLEMENT.
